ELECTRON DEVICE

Ioury G. Maloff, Norristown, Pa., assignor to
 Radio Corporation of America, a corporation of
 Delaware

Application November 9, 1937, Serial No. 173,667

5 Claims. (Cl. 250—158)

This invention relates to electron discharge devices, and, in particular, to electron beam tubes equipped with electrostatic deflection systems.

In cathode ray tubes where it is desired to produce brilliant images, one of the general requirements is the use of highly accelerating voltages which may reach 20,000 volts or more, the high voltage being necessary in order that the electrons impacting upon a luminescent screen shall produce enough luminosity to give the requisite illumination for observation purposes. Such tubes, for example, are used in electrical measurements, and in particular, in television systems. Where the tube is used in electrical measuring systems because of high speed of indication, high illumination values are desirable in order that suitable photographs of the phenomena being studied may be conveniently made, while where such tubes are used for television, it is desirable to have high illumination to alleviate eye strain, and at the same time, make the reproduced images on the luminescent screen easily visible to large groups of people.

The requirements, therefore, upon the cathode ray focusing system commonly referred to as an electron gun, together with the deflecting system, are rather severe from the standpoint of insulation, because of the high voltages, while the use of the high voltages generally give rise to distortions in the recorded phenomena due to the electrostatic fields set up between deflecting plate systems and the support structures.

This is particularly true of the distortions which are set up between the mutually perpendicular electrostatic deflecting system and the support members which serve to hold the deflecting electrode systems in proper alignment. Consequently, one of the main objects of this invention is to overcome the distortions arising between the deflecting plate systems.

Another object of the invention is to provide a much firmer supporting method and means for the electron gun together with the deflecting system.

A still further object of my invention is to provide an improved method of insulating the deflecting electrodes and the electron gun from the support members.

Other and ancillary objects of the invention will be apparent upon the reading of the detailed description taken together with the appended claims.

In accordance with the invention with respect to the elimination of distortion arising between the deflecting plate system and the support mem-

bers, I position intermediate the mutually perpendicular electrode systems a pair of electrostatic shields which are electrically bonded to the metallic support rods which support the deflecting electrodes as well as the electron gun. 5 The electrostatic shields thus provided eliminate any asymmetrical electrostatic fields which might otherwise be set up, and consequently, prevent the beam of electrons from being affected by spurious electrostatic fields which would 10 otherwise be present.

In carrying out my method and means for supporting the unitary assembly of the gun and deflecting system, I make use of a metal plate into which are screwed four relatively large diameter metal rods in a symmetrical array. Attached to the support rods are lateral support members for carrying the deflecting plates, while ring shaped support members are supplied for the electrode gun structure. For purposes of 20 insulation, insulating members are fastened between the deflecting electrode and the lateral support members, while ring insulators are supplied between the ring support members and the electrodes of the electron gun.

Turning now to the drawing, in which

Fig. 1 shows schematically a cathode ray tube embodying my invention.

Fig. 2 shows the cross-section taken at the line 2—2 of Fig. 1; and

Fig. 3 shows the details of supporting deflecting electrodes in accordance with my invention.

I will describe my invention in detail.

Referring now to Fig. 1, an envelope 1 which may be of glass, but preferably for large sized tubes is made of metal, supports at the one end a glass wall 41, upon which is supported a layer of luminescent material 43. The edges of the envelope, which are flanged, are lapped ground as are the edges of the end wall 41 in contact therewith, so that by the use of suitable sealing compounds, an air-tight joint is provided.

It will be understood that this form of structure is used preferably where the size of the tube is so large as not to use a single envelope member because of the gigantic pressure which must be supported by the end wall. Where small sized tubes are provided, the end wall 41 and the envelope 1 may be suitably made from a single glass blank, as is well known in the art. At the opposite end of the envelope, a metal plate 35 lapped ground so as to form a lapped joint with the flanged end of the envelope 1, has supported therefrom four metal rods 5—5. These metal support rods support lateral support members

1 and 17, from which in turn, are insulatedly supported the deflecting plates 3-3 and 21, the insulator elements 13 being interposed between the plates and the lateral support members.

5 The method of support is shown in more detail in Fig. 3 in which the metal rods 5 are shown supporting the lateral support members 7, which have suitable holes drilled in their upper faces through which the rods 5 may pass 10 and which are held in position by set screws 11. The set screws 9 extend through the lateral support member 7 and engage with suitably tapped holes in the insulating member 13. The deflecting plate 3 is supported at an angle with 15 the axis of the tube by counter-sunk set screws extending through the insulating member 13 and engaging with shallow threaded holes in the deflecting plate 3.

Alternatively, the plate 3 may be fastened to 20 the insulating member which may be of ceramic material by a suitable cement. Connection to the deflecting plates is by way of the leads 45, which are spot-welded or soldered to the deflecting plates and which run alongside of the 25 support rods 5, but mounted clear thereof through the use of stand-off insulators. Below the deflecting plates 3 are the electrostatic shield members 15, each shield being electrically bonded to two of the support rods 5, extending beyond 30 the lower edge of the plates 3-3 and in back thereof. Below these, the other set of deflecting plates 21, set at right angles to the first set of deflecting plates, as well as the shields 15, are supported in essentially the same manner as the 35 deflecting plates 3-3 by means of the lateral member 17, which member is locked in place by the set screws 19. The set screws 23 serve to hold an insulator from which the plate 21 is mounted, and a potential connection is afforded 40 by the lead 49, which also runs alongside of the support rods, but held spaced therefrom by stand-off insulators. Below the deflecting plates, the second anode 29 of the electron gun is held 45 in position by a ringed insulator tightly gripping the second anode 29. The ring insulator in turn is supported from a metallic ring support member 39, which is held in position by the set screws 27 inserted in the ring member 39 and engaging with the rods 5. The second anode 50 is electrically bonded to the envelope 1 by means of lead 51 in the applications where a metal tube is used. Where, however, a glass envelope is used, then the second anode may be electrically bonded to the support rods 5. The first anode 55 55 is similarly supported from the support rods 5 by a ring member 39 engaging a ring insulator, which ring insulator has a drive fit over the cylindrical first anode. Suitable connection to the first anode is provided by way of lead 53 passing through the glass press 33. The control electrode 55 is supported from the first anode 31 by means of an internal annular insulator. This insulator has a drive fit with respect to the inner surface of the first anode 31 and a drive fit with respect to the external surface of the control electrode 55. Internally of 60 the control electrode 55, a cathode which may be of indirectly heated type, may be suitably supported and positioned by an annular ceramic insulator. Suitable leads are provided to both the control electrode and the cathode, which leads pass through the glass seal 33, which seal is made air-tight with respect to the metal plate 35.

70 Fig. 2 shows in cross-section in somewhat

more detail the method of supporting the anodes by the use of the ring insulators and support members. In this figure, the second anode 29 is shown in section around which is placed the ring insulator 37, which in turn has the metal ring 39 in contact with it. The insulator, which may be of the ceramic type, is held in position by set screws 25, while the assembly of the metallic ring 39, the insulator 37, and the second anode 29, are conveniently supported from the rods 5 and locked in position by the set screws 27. Thus a very rigid, easily assembled, electron gun and deflecting plate system is provided with excellent provision against displacement by mechanical shock or impact.

15 At the same time the electrical shields 15 prevent fringing from the deflecting plates to the support rods, in the region where the beam would be adversely affected and would, accordingly, produce distortion if it were not for these 20 shields. It should be understood, that where high voltages on the order of 20,000 volts are provided, together with a metal casing such as is shown in the drawing, the metal casing is maintained at ground potential so that liability to 25 shock is guarded against, and accordingly, the support rods are at the same potential as the second anode, while the other electrodes in the system are generally at a lower potential. Since 30 the electrostatic deflecting plates, which are generally supplied with saw-tooth deflection voltages, are generally of negative voltage with respect to the voltage of the casing 1, the difference in potential between the deflecting plates and the support rods would normally produce a 35 distorting electrostatic field through which the beam would necessarily pass. However, by providing a large conducting surface maintained at the same potential as the support rods in back of the deflecting plates, any electrostatic fields 40 set up are outside of the region through which the cathode ray beam passes, and hence, no deleterious effects are encountered.

45 It will, therefore, be understood that this method of confining spurious electrostatic fields to the back of the deflecting plates, enables improved results to be obtained.

Although the invention has been shown as applied to well known electron discharge devices, it is to be understood that the electron discharge devices are merely illustrative of any organization since the invention may be applied to numerous other embodiments without departing from the spirit and scope of the invention.

Having described my invention, what I claim is:

1. A cathode ray tube comprising a metallic envelope flared at one end, a glass end wall sealed to the flared end, a luminescent screen supported from the glass wall, a metal base support plate fastened to the envelope, a plurality of metal support rods supported from the plate, and means to support in register with each other an electron gun and two pairs of deflecting electrodes perpendicular to each other, said support means being affixed to said metal rods.

2. A cathode ray tube comprising a metallic envelope flared at one end, a glass end wall sealed to the flared end, a luminescent screen supported from the glass wall, a support plate fastened to the envelope, a plurality of metal support rods supported from the plate, means to support in register with each other an electron gun and two pairs of deflecting electrodes perpendicular to each other, said support means being affixed to said metal rods, and electrostatic shields sup-

ported from the support rods and intermediate the two pairs of deflecting electrodes.

3. A cathode ray tube comprising a metallic envelope flared at one end, a glass end wall sealed to the flared end, a luminescent screen supported from the glass wall, a support plate fastened to the envelope, a plurality of metal support rods supported from the plate, means to support in register with each other an electron gun and two pairs of deflecting electrodes perpendicular to each other, said support means being affixed to said metal rods, and a pair of rectangular plates intermediate the pairs of deflecting electrodes and electrically bonded to and supported from the support rods.

4. A cathode ray tube comprising a metallic envelope flared at one end, a glass end wall sealed to the flared end, a luminescent screen supported from the glass wall, a support plate fastened to the envelope, a plurality of metal support rods supported from the plate, means to support in register with each other an electron gun and two pairs of deflecting electrodes per-

pendicular to each other, said support means being affixed to said metal rods, and a pair of parallel plates electrically bonded to and supported from the support rods intermediate the pairs of deflecting electrodes and extending in back of one of the deflecting electrodes.

5. In a cathode ray tube, the combination of an electron gun, a pair of deflecting plates in register with the electron gun, a second pair of deflecting plates in register with the electron gun and more remotely positioned than the first pair of deflecting plates, a pair of electrostatic shields positioned in the region intermediate the first and second pairs of deflecting plates, a planar metal support plate, a plurality of metallic rods constituting common means for supporting the electron gun, the electrostatic shields, and the two pairs of deflecting plates, said metallic rods being affixed perpendicularly to said support plate, and connections from said shields to said metallic rods.

IOURY G. MALOFF.
